substantially as shown and described.

DESCRIPTION

FIG. 1 is a perspective view of an electronic device holder in
accordance with the present invention;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof;

FIG. 8 is a perspective view thereof, shown in an environment
of use that includes an unclaimed electronic device;

FIG. 9 is a perspective view thereof, shown in an environment
of use that includes an unclaimed electronic device;

FIG. 10 is a perspective view thereof, shown in an environment
of use that includes both an unclaimed electronic device
and an unclaimed desktop; and,

FIG. 11 is a perspective view thereof, shown in an environment
of use that includes an unclaimed human hand.

In the drawing, the broken lines depict unclaimed environment.

The electronic device shown in FIGS. 8, 9, 10, and 11 may for
